Primary Examiner — Vy Koenig(74) *Attorney, Agent, or Firm* — Paul D. Chancellor; Ocean Law(57) **CLAIM**

The ornamental design for a packaging, as shown and described.

DESCRIPTION

FIG. 1 is an exploded perspective view of a packaging showing my new design;

FIG. 2 is a perspective view thereof in a partially assembled condition of use, shown without the unclaimed insert for clarity of illustration;

FIG. 3 is a side view thereof;

FIG. 4 is a top view thereof;

FIG. 5 is front view thereof; and,

FIG. 6 is a rear view thereof.

The broken lines shown represent unclaimed subject matter and form no part of the claimed design. The shade lines shown represent surface shading and not surface ornamentation.
